UNITED STATES PATENT OFFICE.

ANNA ALBERT HUDGINS, OF ROME, GEORGIA.

BUTTONHOLE-CUTTER AND RIPPER.

SPECIFICATION forming part of Letters Patent No. 560,616, dated May 19, 1896.

Application filed September 14, 1895. Serial No. 562,551. (No model.)

To all whom it may concern:

Be it known that I, ANNA ALBERT HUGGINS, a citizen of the United States, and a resident of Rome, in the county of Floyd and State of Georgia, have invented certain new and useful Improvements in Buttonhole-Cutters and Rippers; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

This invention has for its object the production of a cutter for attachment to the table of a sewing-machine, to a work-table, lap-board, or other convenient place, which is normally concealed and sheathed from danger of accident, and which when turned up for use may be utilized for cutting buttonholes and other slits and for cutting the threads of seams in ripping and for other uses usually convenient for needle-work, the details of all of which will be hereinafter fully set forth.

In the accompanying drawings, Figure 1 is a perspective view of the device attached to the drop-leaf of a sewing-machine and turned up as when in use. Fig. 2 is a section through a fragment of the table or base-board, showing the device approximately full size and open as for use, and also showing the recess for the blade when turned down and out of use. Fig. 3 is a section on the line 3 3, Fig. 2, showing a front elevation and more plainly showing the form of the blade proper. Fig. 4 is a section on the line 4 4, further showing the construction of the blade and its means of attachment to the leaf of the device.

In the figures like reference-characters are uniformly employed in the designation of the corresponding elements of construction.

A is the table of a sewing-machine, of which 45 a is the drop-leaf, merely typifying, however, a base-board of any desired form, such as the top of a work or other table, a lap-board, or a special base of sufficient weight to resist the side thrust in ripping seams, &c.

B is the cutter, which is composed of a leaf b, provided with a screw-hole b', properly countersunk, and a leaf b², pivotally secured

thereto and of any desired conformation, a thumb-nail hold b³ being provided for ease of lifting same when depressed.

C is the blade, which is formed of a lozenge shape with fleam-shaped point and cutting edges c' c² c³, the two former of which lie along the two upper edges, the first, c', extending from the extreme point nearly to the base c, 55 the second, c², extending from said point to the obtuse angle, and the last, c³, lying along the third edge and extending from said obtuse angle to near the juncture of said side with the base. This provides a point for entering 60 and divergent cutting edges for slitting—as, for instance, for cutting buttonholes—the cutting edge c' serving to cut from such point of entry of the point outwardly to the edge of the goods by pulling said goods toward the 65 operator and the edges over and near the obtuse angle serving to cut threads in a seam by simply holding the two joined parts of the garment astride the edge of the blade and moving same upwardly and downwardly 70 across said obtuse angle and along the sides c² and c³, the angle serving to make a shearing or advancing cut.

In ripping seams in expensive goods this cutter is especially advantageous, as both 80 hands are available for manipulating the goods and all danger of cutting the goods is obviated, and also a gentle pull may be given the two parts in a divergent direction, whereby the ripping may be facilitated and some 85 of the stitches pulled out without cutting. Ordinarily one hand wields the knife used in cutting the threads, while the other is used as best it may be to manipulate both parts of the garment, (sometimes difficult to handle 90 with both hands on account of its weight or the curvature or sinuosity of the seams,) or one part of the garment is pinned to the skirt of the operator, while one hand wields the knife and the other holds the goods. The 95 base c is secured to the leaf b² by a screw b⁴, and this fastening is made secure against turning of the blade under pressure by a point c⁴, (same being the corner formed by the turning up of the blade proper,) being bent 100 downwardly and inserted in a depression in the leaf b², as best shown in Fig. 4. This device is attached to the base by means of a single screw d, the leaves b and b² being either

mortised into the said base, as shown in the drawings, and lying with their upper sides flush, or, as would be equally as good, perhaps, being merely screwed to the top of said base and lying entirely thereabove, with the exception of the knuckle and the blade, for both of which it will be necessary to mortise, as seen in Figs. 2 and 3. When folded down, it will be observed that the knife is sheathed and concealed, so as to be inaccessible to children and not liable to obstruct the movement of goods on the table.

Having thus described my invention, what I claim as new, and desire to secure by Letters Patent, is—

In a buttonhole-cutter and ripper, a base, a leaf hinged thereto, a knife composed of an angle-plate the projecting sharpened portion of which is lozenge-shaped, a point bent at the lower end of the angle, the leaf being recessed 20 to receive said point and a screw passing through the base of said angle into the leaf, substantially as and for the purpose specified.

In testimony whereof I hereunto affix my signature in presence of two witnesses.

ANNA ALBERT HUDGINS.
